UNITED STATES PATENT OFFICE.

CHARLES LE G. FORTESCUE, OF WILKINSBURG, PENNSYLVANIA, ASSIGNOR TO
WESTINGHOUSE ELECTRIC & MANUFACTURING COMPANY, A CORPORATION
OF PENNSYLVANIA.

TRANSFORMER.

No. 879,158.

Specification of Letters Patent.

Patented Feb. 18, 1908.

Application filed June 8, 1907. Serial No. 378,013.

To all whom it may concern:

Be it known that I, CHARLES LE G. FORTESCUE, a subject of the King of Great Britain, and a resident of Wilkinsburg, in the county of Allegheny and State of Pennsylvania, have invented a new and useful Improvement in Transformers, of which the following is a specification.

My invention relates to electrical transformers, and it has for its object to provide means whereby a large variety of voltages may be obtained from a transformer by employing a comparatively small number of leads and without causing appreciable unbalance of the magnetic circuits.

In electrical transformers, as now most commonly constructed for commercial use, the windings are provided with leads that may be connected in a plurality of different arrangements in order to obtain a variety of voltage ratios. However, as the windings and leads have heretofore been arranged with respect to each other, considerable unbalance of the fluxes traversing corresponding portions of the magnetic circuits usually occurs, while a relatively large number of leads has been necessary in order to obtain a large or a desired range of voltages. The leads have also been connected near the terminals of the transformer, thus weakening the insulation of the portions of the winding that are ordinarily subjected to the highest voltage strains.

In the present transformer, only a comparatively small number of leads are required for obtaining a large number of voltage steps, and the leads are connected to the windings in such a manner that, when effecting voltage adjustment, correspondingly located portions of the winding are removed from circuit in succession, whereby unbalance of the magnetic circuits is avoided. The insulation of the transformer also is not weakened by the presence of the leads.

Figure 1, of the accompanying drawings, is a diagrammatic view of a portion of a transformer that embodies my invention, and Figs. 2 to 8, inclusive, are views of the terminal block of the transformer which illustrate the connections whereby voltage adjustment may be effected.

Mounted upon a portion 1 of the magnetizable core of the transformer, is a plurality of coils 2 to 19, inclusive, the coils 2, 7, 8, 13, 14, and 19 constituting the low voltage

winding of the transformer, and coils 3, 4, 5, 6, 9, 10, 11, 12, 15, 16, 17, and 18 constituting the high voltage winding. The high voltage winding is divided into three sections, each comprising a group of four coils, and the said sections are interpolated in a symmetrical arrangement with the four sections into which the low voltage winding is divided. Each of the two inner sections of the low voltage winding comprises two coils and each of the outer sections comprises a single coil. The grouping of the coils and the symmetrical arrangement of the groups are provided for the purpose of reducing the leakage and inductance in the transformer, and for preventing, as far as possible, unbalancing of the magnetic fluxes in corresponding portions of the core.

The outer extremities of the coils 2 and 19 are connected, respectively, to terminals 20 and 21 upon a terminal board or block 22, and the inner extremities are connected, respectively, to terminals 23 and 24. Suitable intermediate points, that are located nearer the inner extremities of the coils 2 and 19 than their outer extremities, are connected respectively to the terminals 25 and 26.

The outer extremities of the coils 7 and 14 are connected, respectively, to terminals 27 and 28, and suitable intermediate points of the said coils are connected to terminals 29 and 30, the distances between the said intermediate points and the outer extremities of the coils 7 and 14 being greater than the distances between the intermediate points in the coils 2 and 19, and their inner extremities. If the portions of the winding included between the terminals 27 and 29 and between terminals 28 and 30 are of twice the active length of the portions of the winding that are included between terminals 23 and 25, and between terminals 24 and 26, equal voltage steps may be obtained throughout the range of adjustment.

In Fig. 2 are shown the connections upon the terminal block whereby the maximum voltage of the transformer may be obtained, the terminals 23 and 27 being connected together, as are also terminals 24 and 28, in order to include in circuit all of the low voltage winding.

In Fig. 3, terminals 25 and 27 are connected together, as are also terminals 24 and 28, so that a portion of the winding 2 is excluded from the circuit. The terminals 25 and 27

remain connected together in Fig. 4, and terminals 26 and 28 are also connected together, so that a portion of the winding 19 is excluded from the circuit.

5 In Fig. 5 terminals 23 and 29 are connected together, as are also terminals 26 and 28, portions of each of coils 7 and 19 being then excluded from the circuit.

In Fig. 6 portions of the coils 7 and 14 are 10 excluded from the circuit, since terminals 23 and 29 are connected together, as are also terminals 34 and 30. Portions of windings 3, 7, and 14 are excluded from the circuit in Fig. 7, since terminals 25 and 29 are connected together, as are also terminals 24 and 30.

In Fig. 8 terminals 25 and 29 are connected together, as are also terminals 26 and 30, so that portions of windings 2, 7, 14, and 19 are excluded from the circuit. Thus it is 20 seen that the leads whereby voltage adjustment may be effected are connected to the inner portions of the winding where the voltage strains are not excessive and, consequently, the insulation of the transformer is 25 not weakened by the presence of the leads. Only a comparatively small number of leads to be connected to intermediate points of the coils are necessary in the present arrangement in order to obtain a relatively large 30 number of steps in the voltage. The symmetry of the arrangement of coils is not at all disturbed by the connections illustrated in Figs. 2, 4, 6, and 8, while, with the connections illustrated in Figs. 3, 5, and 7, the 35 symmetrical arrangement is only slightly disturbed, so that little or no unbalancing of the magnetic circuits occurs during voltage adjustment.

It will, of course, be understood that 40 either or both windings of the transformer may be provided with leads, as desired.

I claim as my invention:

1. In a transformer, the combination with primary and secondary windings at least one 45 of which comprises a plurality of sections,

with which the other winding is interpolated to form a symmetrical arrangement, of means for connecting different pairs of points of the said sections to adjust the voltage ratio of the transformer.

2. In a transformer, the combination with primary and secondary windings, each comprising a plurality of sections, 1e sections of the windings being interpolated in a symmetrical arrangement, of means for connecting 55 a plurality of different pairs of points in the sections of one winding between which a section of the other winding is located.

3. In a transformer, the combination with primary and secondary windings each comprising a plurality of sections, the sections of the windings being interpolated in a symmetrical arrangement, of means for connecting a plurality of different pairs of points in the sections of one winding that are symmetrically located with respect to a section of the other winding.

4. In a transformer, the combination with primary and secondary windings, each comprising a plurality of sections, the sections of 70 the windings being interpolated in a symmetrical arrangement, of means for removing from the circuit portions of the sections of one winding between which a section of the other winding is located.

5. In a transformer, the combination with primary and secondary windings, each comprising a plurality of sections, the sections of the windings being interpolated in a symmetrical arrangement, of means for removing 80 from the circuit portions of the sections of one winding that are symmetrically located with respect to the other winding.

In testimony whereof, I have hereunto 85 subscribed my name this 31st day of May, 1907.

CHARLES LE G. FORTESCUE.
